UNITED STATES PATENT OFFICE

ALDEN B. STARR, OF BROOKLYN, NEW YORK, ASSIGNOR TO KNAPP-MONARCH COMPANY, A CORPORATION OF MISSOURI

DESIGN FOR A TOASTER

Application filed February 12, 1930. Serial No. 34,509. Term of patent 7 years.

To all whom it may concern:

Be it known that I, ALDEN B. STARR, a citizen of the United States, residing at Brooklyn, in the county of Kings and State of New York, have invented a new, original, and ornamental Design for Toasters, of which the following is a specification, reference being had to the accompanying drawing, forming part thereof.

The figure of the drawing is a perspective view of a toaster showing my new design.

I claim:

The ornamental design for a toaster substantially as shown.

ALDEN B. STARR.
